UNITED STATES PATENT OFFICE.

HERBERT W. CHENEY, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

PNEUMATIC GOVERNOR.

1,215,621.

Specification of Letters Patent.

Patented Feb. 13, 1917.

Application filed April 27, 1910. Serial No. 558,051.

To all whom it may concern:

Be it known that I, HERBERT W. CHENEY, a citizen of the United States, residing at Milwaukee, in the county of Milwaukee and State of Wisconsin, have invented certain new and useful Improvements in Pneumatic Governors, of which the following is a full, clear, and exact specification.

This invention relates to governors for fluid pressure systems and particularly to that type of governor which includes an electric switch together with suitable means for operating the switch so as to close or open the circuit of an electric motor which 15 drives a compressor when the fluid pressure varies beyond certain predetermined limits.

The object of this invention is to improve the operation of fluid pressure governors, and to provide a governor of durable and 20 compact construction.

The various novel features of this invention will be apparent from the description and drawings and will be particularly pointed out in the appended claims.

25 In the accompanying sheet of drawings, Figure 1 is a side elevation, partly in section and parts being removed, of a governor embodying my invention, the switch being closed.

30 Fig. 2 is a similar view with the switch in open position.

Fig. 3 is another side elevation of my governor looking from the opposite side.

35 Fig. 4 is a partial sectional view taken substantially along the lines 4—4 of Fig. 2 and 4—4 of Fig. 5 looking in the direction indicated by the arrows.

Fig. 5 is a bottom elevation of the same 40 governor.

Fig. 6 is a perspective view of the governor, parts being broken away for the sake of clearness; and

Fig. 7 is a perspective view of the same 45 governor showing the contact mechanism.

The body portion 10 of this fluid pressure 50 governor comprises a boxlike structure forming a comparatively large fluid receiving chamber in which is located the main portion of the switch operating mechanism, a tubular portion 11 for the reception of an energy storing member to be referred to presently, a bracket portion 12 forming a support for a movable contact member, and two covers, one (not shown) for the side 55 and one 13 for the bottom.

Located within the tubular portion 11 is a cylindrical guiding member 14 and a screw 15 provided with a hollow portion 16 which co-operates with the guiding member 14 in receiving and holding in position an energy 60 storing member or spring 17. The screw 15 is turned into the tubular portion 11, and a locknut 18, also engaging a threaded portion of the screw 15, is screwed onto this 65 threaded member 15 up to a point where the nut 18 engages the end of the tubular member 11. To provide a flat pressure surface for working the spring 17, a disk 19 is provided with a projecting portion 20 which fits snugly into the inner portion of one end 70 of the energy storing member or spring 17. Engaging this disk 19 are two more disks 20a which in turn are in engagement with 75 a plunger 21 having a piston 22 and rod 23 one end of which rod 23 slides and is supported in the bored part of a projection 24 of the main body. The other end of the rod 23 is connected to the piston 22 which is provided with a leather packing ring 25 to make a snug fit in the cylindrical guiding 80 member 14. Openings have been provided in the screw 15 and nut 18 so that air might escape should any leak past the piston 22. The piston 22 is adapted to transmit fluid pressure for the purpose of storing energy 85 in the spring 17 and is assisted by two springs 26 and 27 which are mounted upon the rod 23 and also act as buffers. The position of one of these springs 27 may be 90 changed by adjusting one set 28 of the collars 28 and 29 respectively, which engage a threaded portion of the rod 23. The limiting movement of this rod 23 in one direction is regulated by a screw 30, which engages a tapped portion 31 of the projection 95 24. The limiting movement of this rod 23 in the other direction is dependent upon the maximum pressure to which the piston 22 and spring 17 are subjected. This spring or energy storing member 17 which is compressible to a varying extent by variations in fluid pressure can be adjusted by the screw 15 to give a greater or less movement of the piston 22 and rod 23 within the same 100 limits of fluid pressure.

The switch operating mechanism is located and supported within the fluid receiving chamber. Fastened to the bottom of the fluid receiving chamber are two cylinders 32 and 33 respectively in which are located 110

pistons 34 and 35 respectively. The pistons 34 and 35 are connected to a cross arm 36 which is secured to, and turns with, a pin 38. An arm 39 mounted on the pin 38 and having a forked end portion 40 is provided with elongated openings 41 for the reception of projecting portions 42 of a collar 43 which is mounted loosely on the rod 23 and is interposed between the springs 26 and 27.

10 Motion transmitted by the pistons 34 and 35 causes the arm 39 to be shifted to such position as to compress one of the springs 26 or 27 depending upon the positions of the pistons, these springs acting as resilient buffers for the arm 39; and, although the spring 17 and the pressure exerted on the piston 22 are relied on mainly as the operating means for the rod 23, it will be apparent that these spring buffers are effective to transmit a force tending to shift the rod 23. Surrounding the pin 38 are one or more springs 44 having ends 45 and 45^a respectively. One end 45 of the spring is engaged by another pin 46 connected to a crank 47 which is keyed to the pin 38. The other end 45^a of the spring engages a pin 48 located in a shoe 49 of a valve to be referred to presently. When the crank 47 is moved with the arm 39 the pin 46 turns one of the ends of the spring, thereby winding it and storing energy therein.

15 The cylinders 32 and 33 register with ports 50 and 51 respectively which are adapted to register in turn with the fluid receiving chamber and with an air passageway 52 in the slide 53 of the valve 54. Communicating with the air passageway 52 is an exhaust port 55 through which air is exhausted from the cylinders 32 and 33 alternately. Interposed between the slide 53 and the shoe 49 is a spring 56 which presses the slide firmly against the valve seat 57 in opposition to the pressure of air passing through the passageway 52 in the slide 53. Secured to the pin 48 of the shoe 49 is a finger 58 which is pressed upwardly by a spring 59 against the projection 61 of a support 60. This finger 58 has a projecting portion 62 which locks the reciprocatory slide of the valve in certain positions. The valve tripping device consists of a system of links and levers pivoted together. A latch 63 of the tripping mechanism is pivoted to the support 60 and to a link 64 which is pivoted in turn to an arm 65. This arm is also pivoted in the upper part of the support 60 and has a follower portion 66 which is interposed between collars 28 and 29. The other end of the arm 65 engages a pin 67 on the arm 39 for setting the switch operating mechanism in its starting position, as indicated in Fig. 1. In order to trip the slide of the valve the latch 63 is provided with two projections 68 and 69 respectively, which are adapted to engage

the projection 62 of the finger 58. This operating mechanism is adapted to control the valve to govern the operation of the pistons 34 and 35 which transmit motion to the arm or switch lever 39.

20 The switch proper 70, which comprises a movable contact 71 and a stationary contact 72, is located exterior to the fluid receiving chamber and is shown in Fig. 3. The stationary contact is secured to an insulating block 73 which is fastened to the body of the governor. The movable contact finger 74 is pivotally mounted on a pin 75 which is received by a supporting member 76 which in turn is pivotally mounted on a pin 77 located in a bracket 78. This bracket is secured to an insulating support 79 which is also fastened to the body of the governor. In order to transmit motion to the movable contact finger 74 another crank 80 is mounted on the pin 38 and is connected to a link 81 which is pivoted to an insulating support 82, upon which the movable contact finger 74 rests. This insulating support 82 is pivoted on the same pin 75 about which the movable contact finger 74 rotates. A spring 83 interposed between the support 76 and contact finger 74 presses the latter sufficiently to cause good contact between the stationary and movable contacts. When the switch is made to open, an arc is formed between the stationary and movable contacts. To destroy this arc a blast of air is directed across its path, the air being conveyed from the exhaust port 55 by a conduit 84.

25 Having described in general the construction of my fluid pressure governor, its operation will be considered. The fluid pressure governor, as indicated in Fig. 1, is set in its original or starting position. In order to set the governor in this position, one end of the arm 65 is brought into contact with the pin 67 of the arm 39. High pressure air from an air compressor is led into the air receiving chamber by a pipe 85. This compressed air enters one of the air cylinders 33 through its port 51 which as shown at 51^a in Fig. 1 is open to said air receiving chamber, and also exerts pressure against the piston 22 forcing the coils of the spring 17 closer together, thereby storing energy therein, and also presses effectively downward on the upper surface of piston 34. The compressed air which is forced into the cylinder 33 is used for equalizing purposes to assist in forcing the piston 34 down at this stage. Three surfaces, therefore, are effective in transmitting energy during this stage of the cycle. They are the exposed surface of the piston 22, the outer or upper surface of the piston 34, and the inner or under surface of piston 35, the latter surface of which however, acts as an equalizing surface. The arm 39 which is connected through linkages to the piston 35

compresses spring 26 which co-operates with the piston 22 in compressing the energy storing member 17. As the air pressure gradually increases, the piston 22 and the rod 23, to which it is connected, move further into the guiding member 14, and the collar 29, which is mounted on the rod 23, forces the follower 66 in the same direction. As the follower 66 moves in this direction it turns about its pivotal point and forces the arm 65, of which it is a part, downwardly. During this operation the end of the arm 65 which engages the pin 67 moves in a manner to disengage itself therefrom, and the projection 68 of the latch 63 presses downwardly on the projecting portion 62 of the finger 58. Just at the point when the pressure has reached its maximum, the projection 68 forces the projection 62 of the finger 58 down to the outer extremity of the projection 61, and due to the energy stored in the spring 44 the shoe 49, which is engaged by one end of this spring, is forced to the right carrying the slide 53 with it. This valve now occupies the position indicated in Fig. 2, the lower side of piston 35 being connected to exhaust port 55 through port 51, and the lower side of piston 34 being connected to the interior 30 of the main casing through the port 50, thus permitting the admission of air under pressure to the cylinder of the latter piston and the exhaustion of air from the cylinder 33 and causing actuation of the pin 38 in 35 a direction to cause opening of the switch 74, breaking the operating circuit of the pump-driving motor and stopping the pump. This same actuation of the pin 38 also causes the shifting of the arm 39 to the 40 position indicated in Fig. 2 wherein the arm bears on and compresses the abutment spring 27, and causes the pin 46 to engage the spring end 45^a, shifting the spring end 45 into engagement with the pin 48 and tensioning the spring in the opposite direction.

The air exhausted from the cylinder 33 is conveyed through the pipe 84 to the contacts 71 and 72 and is effective to extinguish any arc formed on separation of 50 the contacts.

As the pressure of the air in the main chamber decreases, the piston 22 and its rod 23 are forced back toward their original positions by the energy which is stored 55 in the spring 17. The arm 39, acting through the compressed spring 27, assists the spring 17 in gradually forcing the rod 23 back into its original position. As the rod 23 moves back the follower 66 is also carried, thereby 60 raising the link 64 and causing the latch projection 69 to engage the projection 62 of the finger 58. At the point of minimum air pressure the projection 69 forces the projection 62 of the finger down beyond the 65 projection 61, and due to the energy which

is again stored in the spring 44, the valve operating mechanism and valve are moved back to their first positions thus causing closure of the switch 74 to again start the pump in operation, and also causing shifting of the arm 39 to the position indicated in Fig. 1.

The operation of my governor may be controlled by predetermined conditions not mentioned specifically and it is my intention to include all such means of control; there may be many modifications in the precise form and arrangement herein shown and described and I aim to cover all such modifications which do not involve a departure from the spirit and scope of my invention as defined in the appended claims.

What I claim as new is:

1. In combination, a switch, means for operating said switch comprising a plurality of pistons, a valve for controlling the admission of operating fluid to said pistons, means comprising an element movable in response to predetermined fluid pressure conditions for causing the operation of said controlling valve, and means comprising an operative connection between said pressure responsive element and said switch operating means independent of said valve for causing said switch operating means to assist in the 90 operation of said pressure responsive element.

2. In a fluid pressure governor, the combination of a switch, actuating means therefor comprising a fluid pressure operated piston, a member movable with said piston, a valve for controlling the movements of said piston, valve actuating means, an energy storing member, a rod movable by said latter member, means for flexibly connecting 105 said first member and said rod and permitting said first member to assist in the movement of said rod, and connections between said rod and said valve actuating means for rendering said valve actuating means effective.

3. In combination, a switch having fixed and movable contacts, fluid actuated means for operating said switch, said means including a plurality of pistons one side of 115 each of which is exposed to the same pressure at any instant, a valve for controlling the passage of actuating fluid to and from said pistons, a duct adapted to communicate with the cylinder of one of said pistons for 120 carrying exhaust fluid therefrom to said contacts to destroy arcs formed on the separation of said contacts, said valve simultaneously affording communication between said latter cylinder and said duct and connecting the cylinder of another of said pistons to the source of actuating fluid, and means operable in response to variations in fluid pressure for causing the actuation of said valve.

4. In a fluid pressure governor, a casing, an element within said casing and movable in response to the pressure of fluid in said casing, an energy storing device adapted to absorb energy from and transmit energy to said movable element, a circuit controlling switch, operating means for said switch comprising a piston having one side open to the fluid within said casing, a valve for controlling communication between the interior of said casing and the other side of said piston, and means operable by said movable element on the occurrence of predetermined pressure conditions within said casing for causing the operation of said valve.
5. In a fluid pressure governor, the combination of a casing, an element within said casing and movable in response to the pressure of fluid in said casing, a circuit controlling switch, operating means for said switch comprising a piston, a valve for controlling the admission of actuating fluid from said casing to said piston, means for actuating said valve comprising a spring operatively associated with said switch and placed under stress on operation of said switch, a latch for holding said valve-actuating means against operation, and means operable by said movable element for causing the release of said latch.
6. In a fluid pressure governor, a casing, an element within said casing and movable in response to the pressure of fluid in said casing, a circuit controlling switch, operating means for said switch comprising a piston having one side exposed to the fluid in said casing, a valve for controlling communication between the interior of said casing and the other side of said piston, and means operable by said movable element on the occurrence of predetermined pressure conditions within said casing for causing the operation of said valve.
7. In a fluid pressure controller, the combination of a switch, means for actuating said switch comprising an operating shaft and a piston for actuating said shaft, a member movable in response to variations in fluid pressure, one side of said piston being continually exposed to the same pressure as said movable member, a valve for controlling communication between the other side of said piston and either operating pressure or exhaust, means for actuating said valve comprising resilient means associated with said switch operating means, latching means for holding said valve against operation, and means actuated by said movable member for controlling said latching means.
8. In a fluid pressure controller, the combination of a switch, means for actuating said switch comprising an operating shaft and a plurality of pistons for actuating said shaft, one side of said pistons being exposed to the same pressure at any instant, a valve for controlling communication between the other side of each piston and either operating pressure or exhaust, and a member movable in response to variations in fluid pressure for causing the operation of said valve.
- Milwaukee, Wisconsin, April 21, 1910.
- In testimony whereof I affix my signature, in the presence of two witnesses.
